(57) **CLAIM**

The ornamental design for a nasal dilator device, as shown and described.

DESCRIPTION

FIG. 1 is a front perspective view of a nasal dilator device, showing my new design;

FIG. 2 is a front view of the nasal dilator device of FIG. 1; FIG. 3 is a back view of the nasal dilator device of FIG. 1; FIG. 4 is a left side view of the nasal dilator device of FIG. 1;

FIG. 5 is a right side view of the nasal dilator device of FIG. 1;

FIG. 6 is a top view of the nasal dilator device of FIG. 1; and, FIG. 7 is a bottom view of the nasal dilator device of FIG. 1.

The broken lines that are immediately adjacent to the claim, and define unshaded regions, represent the bounds of the claim, while all other broken lines are directed to environment; the broken lines form no part of the claimed design.
